UNITED STATES PATENT OFFICE.

HENRY HARGER, OF LOST RIVER, IDAHO.

GEOGRAPHICAL GLOBE.

No. 895,263.

Specification of Letters Patent. Patented Aug. 4, 1908.

Application filed November 7, 1907. Serial No. 401,098.

To all whom it may concern:

Be it known that I, HENRY HARGER, a citizen of the United States, and a resident of Lost River, in the county of Blaine, State of Idaho, have invented certain new and useful Improvements in Geographical Globes, of which the following is a specification.

While my improved globe is adapted for general use it is particularly intended for use in schools. It is hollow and sectional and provided with means for securing the sections detachably together and to the axis upon which the globe revolves in a suitable frame.

In connection with the globe proper I employ a curved and graduated ruler adapted to move or swing around the globe and for use in indicating and drawing meridians and parallels on the surface.

The details of construction and arrangement and combination of parts are as herein-after described, and illustrated in the accompanying drawings, in which,

Figure 1 is a sectional view of the globe and a side view of the frame in which it is supported and adapted to rotate. Fig. 2 is a detail section of the polar section of the globe. Fig. 3 is a perspective view of the lower portion of the graduated ruler. Fig. 4 is a transverse central section of the globe or a plan view of the lower hemisphere, the graduated ruler being in section. Fig. 5 is a side view of the globe together with the graduated ruler. Fig. 6 is a detail section showing the notched disk or wheel with pawl which is applied to the lower end of the axis of the globe for holding it fixed in any adjustment.

The hollow globe A is supported in a frame consisting of a horizontal base portion B and a curved vertical bar B'. The body of the globe is hollow and may be formed of hemispherical sections or a great number of sections. Thus, in this instance each hemisphere is divided into four sections all of like dimensions. The meeting ends of the several sections are secured together at the poles by means which will be presently described. The globe revolves upon an axis C, arranged at the usual angle of twenty-three degrees, having pointed ends, one of which is stepped in the frame at e and the other enters a conical depression in the end of the clamping-screw D which is arranged in the upper end of the bar B'. On the lower end of the axis C is secured a toothed or ratchet wheel E—

see Figs. 1 and 6. A spring pawl or dog e is pivoted adjacently and its free end engages the disk E. In practice it is preferred that the disk E shall have thirty-six notches so that when the globe is rotated and stopped and held by means of the pawl, the distance moved will be one degree on the surface of the globe. The axis C passes through the alined sleeves F which are of equal length and similarly constructed and arranged mainly within the globe, their outer ends projecting slightly from the polar ends of the same. A nut f—see Fig. 2—is applied to each sleeve F on the inside of the globe, and such nut abuts a plate G which is concavo-convex in form. A similar plate G' is applied on the outer side of the globe. A nut f' is applied to each sleeve F exteriorly to the plate G' and a jam nut f² is screwed on the axis C and abuts the adjacent end of the sleeve, and also the nut f'.

It will now be understood that the polar corners of the sections constituting each of the hemispheres of the globe lie and are clamped between the concavo-convex plates G, G', and that they may be readily detached by screwing the nut back on the sleeve and axis. In order to hold the meeting side edges of the several hemispherical sections in due juxtaposition with each other I prefer to employ dowel pins H—see Fig. 5—the same being held in one section and the projecting pin adapted to enter the socket in the adjacent one as will be readily understood.

By the above described construction of the globe it is apparent that it is adapted to be made very large or of great diameter, say five feet or more, and that the two hemispheres or the several sections of the hemisphere may be easily and quickly detached from each other when required or desired for any purpose. This is particularly advantageous for packing and storing or shipping the globe and also for enabling students to inspect, or make drawings from, particular portions or sections, since a section may be conveniently set on a desk or table.

For supporting the globe sections at the diameter of the globe I employ brace and tie rods I, which are arranged radially as indicated in Figs. 1 and 4, their inner ends being screwed into collars c' that are applied to the meeting ends of the alined sleeves F, while their outer ends are similarly engaged with clips or brackets i which are riveted or bolted

to the circumferential hoops J, as shown in Figs. 1 and 4. Each hoop J extends around the inner side of the globe adjacent to the diameter of the same, the two hoops thus 5 lying juxtaposed. The ends of the rods J are screw threaded in opposite directions to adapt them to be readily inserted and removed from their connections.

The curved ruler K having central lateral 10 extension K', both portions being graduated in degrees of latitude and longitude, is applied in connection with the globe proper, both parts K, K', being curved concentrically with the globe and so attached to the 15 axis C or rather to the projecting ends of the sleeves F that it may rotate or swing around the globe and thus be set in any required position. The ends of the longer ruler K are provided with notches k adapted to receive 20 the projecting ends of the sleeves for the nut f' applied thereto, and a hook k' is pivoted adjacently and adapted to pass around the nut so as to secure the ruler from accidental detachment and yet permit it to be detached 25 whenever required.

It will be seen that the longer ruler K is serviceable for indicating meridians on the globe surface, while the horizontal one K' is similarly available for indicating longitude. 30 Both may also be used by a pupil for drawing meridians and parallels on a blank globe, an exercise in which pupils may require instruction.

What I claim is:

35. 1. The improved geographical globe constructed hollow and in sections, an axis passing through the same, sleeves applied to said axis interiorly of the globe, concavo-convex clamping plates applied interiorly and exteriorly of the globe, and nuts applied to the said sleeves and the axis for clamping the globe sections and preventing movement on the axis, substantially as described.
40. 2. The improved geographical globe constructed hollow and in sections, an axis interiorly of the globe passing through the same, sleeves applied to said axis and also

projecting from the polar portions of the globe and provided thereat with screw threads, and means applied to the outer ends 50 of the sleeves and axis for preventing movement of the globe sections outwardly or from each other, substantially as described.

3. The improved geographical globe constructed hollow and in sections whose edges 55 meet upon the diameter of the globe, an axis passing through the globe, and radius rods extending between the axis and the diametrical edges of the globe sections substantially as described.

4. The improved geographical globe having a hollow body formed in sections which meet at the diameter of the globe, an axis extending through the globe, hoops arranged 60 interiorly of the globe sections and juxtaposed at the diameter of the same, and radius tie-and-brace rods extending between the axis and said hoops and detachably connected therewith, substantially as described.

5. The improved geographical globe constructed hollow and in sections which meet upon the diameter of the globe, and an axis extending through the globe, circumferential hoops arranged at the diametrical edges of the sections and juxtaposed as shown, 75 threaded sockets provided on the axis and other threaded sockets provided on the respective hoops, and radius rods which are screw-threaded in opposite directions and adapted to enter the said sockets as and for 80 the purpose specified.

6. The combination with a globe proper, and an axis whose ends extend beyond the polar ends of the same, of a ruler extending between the poles and graduated in degrees 85 indicating latitude, the ruler having notched ends adapted to receive the axis, and provided with means for securing it detachably on the axis, substantially as described.

HENRY HARGER.
